UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEAM-TABLE.

1,227,106.

Specification of Letters Patent. Patented May 22, 1917.

Application filed October 12, 1914. Serial No. 866,296.

To all whom it may concern:

Be it known that I, HENRY F. BECHMAN, a citizen of the United States, residing at Battle Creek, in the county of Calhoun and 5 State of Michigan, have invented certain new and useful Improvements in Steam-Tables; and I hereby declare that the following is a full, clear, and exact description thereof, reference being had to the accompanying drawings, which form part of this 10 specification.

This invention is an improvement in drying tables for drying matrices and the like, and is particularly designed for use in machines in which pressure is applied by mechanically controlled means, whereby any 15 desired degree of pressure may be applied and the article held under such pressure for any desired length of time and then released.

In large machines of this type the tables 20 are heated, usually steam heated, so that the matrix will be dried while it is being pressed, and in the practical operation of these machines, especially those of large size as heretofore made, difficulty has been experienced because of the unequal expansion of parts, as the table supporting the matrix upon being heated expands more than the yoke supporting the platen, and as a result the yoke 25 is sprung or distorted slightly, but to an extent sufficient to cause a slight displacement of the platen and consequent imperfections in the work; and this unequal expansion impairs the life of the machine because the great strains exerted on the bolts uniting the 30 yoke to the table ultimately loosens or breaks them, and it is most essential to accurate work that the yoke and table shall be rigidly united and immovably held in fixed relation to each other.

The object of the present invention is to overcome the unequal expansion of the yoke and table and obviate the strain upon the connections therebetween, and insure perfect 45 action of the platens and uniformity in the work. I will explain the invention in connection with the machine illustrated in the accompanying drawings, in which—

Figure 1 is a side elevation of the complete 50 machine.

Fig. 2 is a detail end elevation thereof.

Fig. 3 is a detail longitudinal section through the yoke and table looking from the front of the machine.

55 While the drawings show a steam heated

table, which is the most generally used type, the invention is not limited to that form of construction but is applicable and desirable in tables heated by any other means, and it is not my desire to be limited to the exact 60 form and type of table illustrated.

Referring to the drawings, 1 designates the table of the machine which is supported upon suitable standards in the usual manner. Upon this table and extending longitudinally thereof is a yoke or arch 1^b which is supported upon the table by its end portions 1^c preferably formed integral with the yoke and secured to the table by means of through bolts 1^d and nuts 1^e, as shown. 70

The table and arch, as shown, are preferably made long enough to accommodate two platens 2 arranged side by side, and which may be used separately or together; such table being especially adapted for pressing a 75 "double page" or "truck" page matrix, that is, one double sized matrix covering two pages, which requires the use of both platens; and the machine can also operate upon two single page matrices placed side by 80 side.

Each platen 2 is preferably suspended on a rod 2^a connected by links 2^b to a lever 3 pivoted on lugs 1ⁿ rising from the yoke as shown, and the rear end of lever 3 is connected by a link 3^a to one end 4 of a pressure regulating device comprising a frame composed of end pieces 4, 4^a, connected by bolts 4^b, and a rod 4^c sliding through plate 4^a and having a nut 4^d on its upper end, and 85 its lower end connected to a pitman rod 5^a. A spring 4^e is interposed between the nut 4^d and plate 4^a. The other end of pitman 5^a is connected to a crank pin 5^b on a crank gear 5, which is preferably a worm gear and is 90 operated by a worm 6^a secured on a shaft 6 journaled in brackets on the main frame. 95

On each shaft 6 is a loose pulley 6^c provided with a clutch face adapted to be engaged by a clutch member 7 on a sleeve 7^a 100 slidably mounted on shaft 6 between the worm 6^a and the pulley, said sleeve 7^a being splined to the shaft so that when the clutch 7 is engaged with the pulley the worm 6^a will be driven. On the other end of sleeve 7^a is 105 a friction member 7^b which is adapted to engage an opposed friction member 6^x fixed to the worm; the parts being so arranged that when the clutch is disengaged the friction members are brought into engagement, and 110

- vice versa. The sleeve 7^a may be shifted at the will of the operator by means of a lever pivoted on the frame and having a short arm 8 engaging the clutch sleeve, and a long arm 8^a extending inwardly and pivotally connected at 8^c to the rear arm of a controlling lever 9, pivoted at 9^a on the main frame and having its front arm 9^b connected by a rod 9^c to a treadle-lever 9^d which may be held in normal position by means of a spring 9^e. A roller 8^d is attached to the arm 8^a and is adapted to engage with cams 5^x and 5^y formed on or attached to the inner face of the gear 5. These cams have gaps 5^z between their adjacent ends into which gaps roller 8^d can enter as indicated in the drawings, and the lever 9, under the influence of spring 9^e, will cause roller 8^d to move inward and enter a gap 5^z. Whenever the roller 8^d enters a gap 5^z the clutch will be disengaged and the friction surfaces engaged; but the operator, by depressing the treadle 9^d, can cause lever 9 to depress lever 8^a and disengage the clutch faces 7^b, 6^x, and engage the clutch 7 with the pulley 6^c, and at the same time move roller 8^d out of the notch 5^z and it will be held out of this notch by the cam 5^x or 5^y until the gear 5 has made a one-half revolution.
- 30 The means for operating the platens are substantially similar in construction and operation to those shown and claimed in my application for pressure mechanism filed April 22, 1912, Serial No. 692,334.
- 35 In the illustrated form of present invention the table 1 is provided with a steam chamber 1^a, beneath the yoke, into which steam can be introduced by means of the pipe S¹ connected to a pipe S leading to any suitable steam supply (not shown). The yoke 1^b is also provided with a steam chamber 1^s which is also connected by a pipe S² to the steam supply pipe S. The chambers 1^a and 1^s may be connected by pipes s¹ and s² to an outlet pipe s.
- 40 In the actual machines the table 1 would be about 68 inches long, and when such table is heated it expands about one-tenth of an inch; and the yoke 1^b as ordinarily constructed (i. e., without a steam chamber) would not expand equally with the table, and as such yoke must be rigidly and tightly secured to the table the expansion of the table would cause the yoke to spring and 45 loosen or shear the fastening bolts and throw the platens out of true parallelism with the table, causing imperfect work. To overcome these defects I make the yoke hollow and connect the chamber therein with the steam supply, so as to heat it equally with the steam table, and therefore as the yoke and table are equally heated they both expand equally, and in this way the bolts 50 1^d which fasten the yoke to the table are not affected and a secure and uniform re-

lation between the yoke and table is maintained.

If the yoke was not heated it would not expand with the table and would spring, as stated, and this would throw the platens out of true parallelism with the surface of the table and produce unequal, imperfect, surface work; and also cause the fastening bolts to loosen; but by heating the yoke and the table equally all these objections are overcome; and furthermore, by providing two accurately operating platens, I can either operate them both simultaneously to press one double page matrix or they can be operated independently to simultaneously press two single page matrices.

The pulleys 6^c may be simultaneously driven from a suitable driver by a belt, not shown, running over said pulleys and over an idler 6^t mounted upon the frame.

The machine shown operates as follows:

The machine normally stands with the rollers 8^d in the gaps 5^z between the cams 5^x and 5^y, the platens being then in highest position. After the work has been adjusted on the table beneath a platen the operator depresses the outer end of the related treadle 9^d thereby throwing roller 8^d out of the gap and simultaneously engaging the clutch 7 with the pulley 6^c; whereupon motion is imparted to the gear 5, and as gear 5 turns the outer end of lever 3 is depressed, consequently lowering the platen with great power until the gear 5 has made a half revolution and the roller 8^d again enters a gap 5^z between the cams 5^x, 5^y, whereupon the clutch is thrown out of engagement, and the gear 5 stops; this holds the platen down under pressure, the amount of pressure being regulable by adjusting the length of the spring pressure-regulating connections between lever 3 and crank pin 5^b, so that any desired pressure may be applied by the platen, but a dangerously excessive pressure will be prevented by the yielding of spring 4^c.

While compression is on and 5^b is at its lowest point the spring should always be slightly compressed, to insure that the desired pressure for which the machine is set shall be maintained evenly and constantly. When the operator wants to remove the work he again depresses the treadle lever 9^d, thereby disengaging roller 8^d from the gap 5^z and reengaging the clutch, and gear 5 will then be rotated another half revolution until the crank pin 5^b has reached its uppermost position and the roller 8^d again enters a gap 5^z between the cams, whereupon the machine is stopped, as before, until the operator wishes to again lower the platen.

What I claim is:

1. In a steam table the combination of a hollow steam heated table, a hollow steam heated yoke mounted upon said table, a

platens supported by said yoke, and platen operating devices.

2. In a steam table the combination of a hollow table, a hollow yoke mounted upon said table, a platen supported by said yoke, and platen operating devices; with means for supplying steam to the chambers in the table and in the yoke to heat the same uniformly, as and for the purpose specified.

10 3. In a compressor, the combination of a steam table, a hollow steam heated yoke thereon, a pair of side by side platens operatively suspended from said yoke, and means for operating said platens independently, said platens being adapted to coöperate upon a large matrix, or to operate separately upon smaller matrices, and means for supplying steam to the table and yoke.

20 4. In a mechanical compressor steam table, the combination of a steam heated table, a steam heated yoke fastened to said table, a pair of side by side platens operatively suspended from said yoke, and means for operating said platens independently, said platens being adapted to simultaneously operate upon a double page matrix or to operate separately upon single page matrices.

25 5. In a steam table, the combination of a hollow table, a hollow yoke bolted to said table, a pair of side by side platens opera-

tively suspended from said yoke adapted to simultaneously operate upon a double page matrix or to operate separately upon single page matrices, means for operating said platens independently, and means for conducting steam to the chambers of the yoke and table to heat the latter uniformly, as and for the purpose set forth.

40 6. In a mechanical compressor steam table, the combination of a table having a steam chamber therein, a yoke connected with the table and having a steam chamber therein, a platen operatively suspended from said yoke, means for simultaneously admitting steam into the chambers of the table and of the yoke to heat the table and the yoke to prevent injurious unequal expansion of the table and yoke and maintain 45 parallelism between the surface of the table and platen, substantially as described.

7. In a compressor or drying table, the combination of a hollow table, a hollow platen-supporting means and means for simultaneously and correspondingly heating both.

In testimony that I claim the foregoing as my own, I affix my signature in presence of two witnesses.
